LOOSE-LEAF BINDER

George H. Dawson, Needham, Mass., and Paul O. Unger, Elmhurst, Ill., assignors to Wilson-Jones Company, Chicago, Ill., a corporation of Massachusetts

Application September 2, 1943, Serial No. 500,879

4 Claims. (Cl. 129—24)

This invention relates to a loose leaf binder and is particularly concerned with the substitution of wood ring carrying plates for conventional steel plates.

It is an object of this invention to provide a loose leaf binder having wood ring carrying plates with a metal toggle mechanism. It is a further object of this invention to provide means for properly tensioning the binder to insure retention of the rings in either open or closed position. Other objects of the invention will become apparent upon reading the following description, taken in conjunction with the accompanying drawings, in which:

Figure 1 is an end view showing a binder embodying our invention with the rings in closed position;

Figure 2 is a cross-sectional view of the binder shown in Figure 1 showing the rings in open position;

Figure 3 is a fragmentary view similar to Figure 2 showing a modified form of the invention;

Figure 4 is a fragmentary top plan view showing the embodiment of Figures 1 and 2;

Figure 5 is a disassembled perspective view of the toggle mechanism; and

Figure 6 is a fragmentary cross-sectional view showing another embodiment of the invention.

In the drawings, the reference numeral 2 indicates the back of a loose leaf binder to which cover members 3 and 4 are hinged in any suitable manner. A plurality of spring clamps 5 is secured to the back member 2 by any suitable means. The spring clamps are arranged transversely in the back member and have their outer edges curled, as indicated at 6.

A pair of wood ring carrying plates 8 and 9 is arranged longitudinally in the back member with their outer edges spaced inwardly of the curled edges 6 of the spring clamps 5. A plurality of ring sections 10 is secured to the wood plates 8 and 9 in any suitable manner. The ring carrying plate 8 is provided on its under surface with a recess 11, and a stop member 12 secured to the ring carrying plate 8 by means of screws 13 has one end projecting into the recess 11 to engage the ring carrying plate 8 to limit the vertical movement of the ring carrying plates when the ring sections 10 are moved to open position.

The toggle mechanism comprises a pair of pins 14 each having a bifurcated end 15. The pins are driven into the wood ring carrying plates as indicated in Figures 1, 2 and 4 with the bifurcated ends of each pair disposed at right angles so as to provide a secure working engagement between

the ends of the pins 14. The pins 14 fit snugly in the wood ring carrying plates 8 and 9, but in order to prevent their working loose it is preferred to drive staples in the outer longitudinal edges of the ring carrying plates to engage the outer ends of the pins 14. These staples, indicated at 16, also provide a smooth metal edge which slides into the curled portions 6 of the spring clamps 5 when the sheet retaining unit is positioned in the binder. The rounded edges 17 facilitate the assembly operation.

The staples 16 are provided with a notch 18 on the outer edge. The spring clamp 5 is provided with a depressed portion 19 which is adapted to engage the notch 18 to retain the toggle mechanism in the desired longitudinal position relative to the binder when it has been assembled.

The tension with which the ring sections 10 are held in open or closed relationship is governed by the co-operation between the toggle mechanism and the spring clamps 5.

The embodiment illustrated in Figure 3 is similar to that hereinabove described except that the inner ends of the pins 14' are provided with straight ends instead of bifurcated ends and are maintained in working relationship by means of a sleeve 20 which fits over the inner ends of both pins 14'.

In the embodiment illustrated in Figure 6 the bifurcated ends 15 of the pins 14 are replaced by a cone 21 provided on the inner end of one pin 22, and a complementary recess 23 provided in the inner end of the other pin 24.

Although we have described one embodiment of our invention in considerable detail, it will be understood that the description thereof is illustrative rather than restrictive, as many details may be modified or changed without departing from the spirit or scope of our invention. Accordingly, we do not desire to be restricted to the exact details of construction described, except as limited by the appended claims.

We claim:

1. In a loose leaf binder, a pair of wood ring carrying plates, a spring clamp embracing the outer longitudinal edges of said ring carrying plates, and a pin secured to each of said plates, said pins having their inner ends engaged to permit a toggle motion by said plates.

2. In a loose leaf binder, a spring clamp, a pair of non-metallic ring carrying plates arranged in said spring clamp, each of said plates having a pin driven therein, and a metal staple driven into each ring carrying plate and engag-

ing the outer end of one of said pins, the inner ends of said pins being interengaged to permit a toggle motion by said ring carrying plates.

3. In a ring binder, a back member, a spring clamp secured to said back member, a pair of wood ring carrying plates each having its outer edge engaged by said spring clamp, and a pair of pins driven into said ring carrying plates, said pins having their inner ends engaged to maintain said ring carrying plates in position with their outer edges engaged by said spring clamp while permitting arcuate movement of said ring carrying plates on axes coincident with their outer longitudinal edges.

4. In a loose leaf binder, a plurality of spring clamps, a pair of non-metallic ring carrying plates arranged in said spring clamps, said ring carrying plates having a toggle motion to cause
5. the rings carried thereby to open and close, and a pin driven into each of said ring carrying plates, said pins having bifurcated interengaged inner ends, and means secured to one ring carrying plate engaging said other ring carrying plate
- 10 to maintain said ring carrying plates in said spring clamps while permitting said toggle motion.

GEORGE H. DAWSON.
PAUL O. UNGER.
